No. 727,169.

PATENTED MAY 5, 1903.

C. A. MANKER.

COUNTER GRAVITY SCREW PROPELLER.

APPLICATION FILED APR. 10, 1902.

NO MODEL.

UNITED STATES PATENT OFFICE.

CAREY ALAN MANKER, OF PEARL, ILLINOIS.

COUNTER-GRAVITY SCREW-PROPELLER.

SPECIFICATION forming part of Letters Patent No. 727,169, dated May 5, 1903.

Application filed April 10, 1902. Serial No. 102,324. (No model.)

To all whom it may concern:

Be it known that I, CAREY ALAN MANKER, a citizen of the United States, residing in Pearl, in the county of Pike and State of Illinois, have invented certain new and useful improvements in Counter-Gravity Screw-Propellers, of which the following is a full, clear, and exact description, reference being had to the accompanying drawings, forming part of this specification.

My invention relates to a screw-propeller for navigation and embodying a construction by which the propeller-blades are caused to poise and counterpoise each other and act against the force of gravitation while furnishing propulsive action, so that the vessel to which the propeller is applied not only exerts power for propulsion, but also serves to buoy or lift a vessel and sustain it in order that the displacement and resistance of the medium through which the vessel is passing will be materially reduced owing to the decrease in the action of the inertia of the water against the vessel. To obtain the desired result, I so construct the propeller that its blades will have a variation of movement in their downward and upward strokes, thereby causing them to exert a sustaining or lifting impingement at both horizontal sides of the propeller. The essential characteristic by which such result is obtained lies in the use of swingingly-mounted propeller-blades and mechanism whereby the blades are caused to travel with accelerated speed on their downward stroke and with lessened speed on their upward stroke, thereby rendering their action in counterpoise to each other at all times for sustaining effect against the impinging medium beneath them.

The invention consists in features of novelty hereinafter fully described, and pointed out in the claims.

Figure I is a vertical longitudinal section of my propeller. Fig. II is a vertical cross-section taken on line II II, Fig. I. Fig. III is a view of the propeller-blade-actuating crank-shaft gearing. Fig. IV is a view showing the propeller-blade-actuating crank-shaft and one of the blade-rockers in cross-section and one of the rocker-arms and bearing-boxes fitted to said crank. Fig. V is a cross-section taken on line V V, Fig. IV. Fig. VI

is a bottom view of the propeller-runner and propeller.

1 designates the lower end of a hanger by 55 which the propeller is sustained.

2 designates the runner of the propeller, which tapers forwardly from the hanger 1 in wedge shape, as seen in Fig. VI, so that it will offer the least resistance to the medium 60 through which it passes. The runner 2 is secured to the hanger by a series of screw-rods 3, one of which is shown in Fig. I.

4 designates a bearing member set into the rear end of the runner 2 beneath the hanger 65 1 and held to said runner by one or more retaining-screws 5. The bearing member 4 is provided with a rim 6 and carries a stem 7, positioned centrally of said rim. The rim 6 is completed at the top by an extension 1^a of 70 the hanger 1.

8 is a bushing seated in the rim 6 and held therein by retaining-screws 9.

10 designates a power-shaft which extends downwardly through the hanger 1 and to 75 which power may be applied by a suitable motor. Fixed to the lower end of the shaft 10 is a beveled pinion 11, positioned in a recess 12 in the bearing member 4.

13 designates a rotatable barrel that is 80 loosely fitted to the bearing-member stem 7 and is journaled in the bushing 8. The inner end of this barrel is provided with a beveled gear 14, that is arranged in mesh with the beveled pinion on the power-shaft 10. 85

15 designates a crank-shaft extending longitudinally through the bearing member 4 and through the stem 7 of said member in a position eccentric to the center of said stem.

15' is the crank-arm of said shaft.

16 designates a series of rockers loosely mounted in the barrel 13 and extending longitudinally thereof. Each of the rockers 16 carries a propeller-blade 17.

18 designates arms fixed to the rockers 16 95 and provided with longitudinal apertures 19, in each of which the arm 15' of the crank-arm 15 is adapted to operate.

20 designates flanged slide-boxes fitted in the longitudinal apertures of the rocker-arm 100 18 (see Figs. IV and V) and in which the crank-arms are journaled, each slide-box being provided with an oil-well 21, (see Fig. V,) from which lubricant is supplied to the bear-

ings of the crank-arms on introduction there-
into through an orifice 22.

23 designates a gear-wheel fixed to the
crank-shaft 15, (see Figs. I and III,) and 24
is a worm arranged in mesh with said gear-
wheel and carried by a turn-rod 25, which
leads upwardly through the hanger 1. The
turn-rod 25 is adapted to be rotated to cause
the worm 24 to turn the gear-wheel 23 and
thereby impart rotation to the crank-shaft 15.

26 is an oil-well in the barrel 13, that is
closed by a plug 27. This well is adapted to
receive lubricant to be supplied to the inner
and outer surfaces of the barrel 13 where it
15 contacts with the bearing-member stem 7 and
bushing 8.

In the practical use of my propeller the
parts are operated as follows: Upon rotation
of the power-shaft 10 the beveled pinion 11 is
20 rotated to impart rotation to the barrel 13
through the medium of the intermeshing bevelled
gear 14, carried by said barrel. By this
means the propeller-blades are rotatably
moved in the medium through which they are
25 traveling. The crank-shaft 15, which is the
prime factor in obtaining the counterpoising
action of the propeller-blades, is actuated
through the medium of rotation of the turn-
rod 25, which causes the worm 24 to rotate
30 the gear-wheel 23, and consequently the
crank-shaft. The turn-rod may be actuated
in any desirable manner. Upon rotation of
the crank-shaft its arm 15', having journal
connection with the arms 18 of the rockers 16,
35 causes said arms to be rocked and by their
rocking swing the propeller-blades into va-
rying positions with relation to each other.
By this arrangement I provide for an acceler-
ated speed of the blades at one horizontal
40 side of the propeller-barrel, while the arm of
the crank-shaft is traveling upwardly at the
opposite side and thereby exerting an in-
creased leverage upon the corresponding arm
18 of the descending propeller-blade. At the
45 same time the crank-shaft arm being closer
to the rocker 16 or axis of the ascending pro-
peller-blade has decreased leverage upon the
arm 18 of said blade, thereby causing the as-
cending blade to be held back and its speed
50 diminished in the same ratio as the corre-
sponding descending blade is forced down-
wardly or forwardly with accelerated speed.
It will be seen that I therefore acquire a
counterpoise action of the descending and
55 ascending blades in impingement against the

medium in which they are moving by which
the propeller and vessel to which they are ap-
plied are constantly buoyed and sustained in
the manner hereinbefore referred to.

I claim as my invention—

1. The combination with a revoluble pro-
peller blade or carrier, of means for revolving
said carrier, a rotatable crank-shaft mounted
within said carrier, rockers mounted in said
carrier, propeller-blades carried by said rock-
ers, arms carried by said rockers within which
said crank-shaft is arranged to operate, and
slidable boxes journaled to said crank-shaft
and respectively mounted in said rocker-arms,
substantially as set forth. 65

2. The combination in a propeller, of pro-
peller-blades, means in which said blades are
swingly supported, arms carried by said
blades, bearing-boxes reciprocally mounted
in said arms, a crank-shaft having an arm
70 positioned in said bearing-boxes, and means
for rotating said crank-shaft, substantially
as and for the purpose set forth. 75

3. The combination in a propeller, of a bear-
ing member, a stem carried by said bearing
80 member, a bushing seated in said bearing
member, a barrel arranged in said bushing,
means for rotating said barrel, propeller-
blades swingingly mounted in said barrel,
and means whereby said propeller-blades are 85
caused to travel with accelerated speed dur-
ing the downward strokes, substantially as
set forth.

4. The combination in a propeller, of a bear-
ing member, a stem carried by said bearing
90 member, a bushing seated in said bearing
member, a barrel arranged in said bushing,
means for rotating said barrel, propeller-
blades swingingly mounted in said barrel, a
crank-shaft provided with arms and extend-
95 ing through said bearing-member stem ec-
centrically to its transverse center, arms car-
ried by said blades and bearing-boxes recip-
rocally mounted in said blade-arms in which
said crank-shaft arm is positioned, substan- 100
tially as set forth.

In testimony whereof I have signed my
name to this specification, as well as to the
drawings herewith, in the presence of two
subscribing witnesses.

CAREY ALAN MANKER.
